UNITED STATES PATENT OFFICE.

CUMMINGS C. CHESNEY AND HERBERT W. SMITH, OF PITTSFIELD, MASSACHUSETTS, ASSIGNORS TO STANLEY ELECTRIC MANUFACTURING COMPANY, OF SAME PLACE.

ELECTRIC SWITCH.

SPECIFICATION forming part of Letters Patent No. 674,076, dated May 14, 1901.

Application filed July 23, 1900. Serial No. 24,528. (No model.)

To all whom it may concern:

Be it known that we, CUMMINGS C. CHESNEY and HERBERT W. SMITH, citizens of the United States, residing at Pittsfield, county 5 of Berkshire, State of Massachusetts, have invented certain new and useful Improvements in Electric Switches, of which the following is a full, clear, and exact description.

Our invention relates to an electric switch, 10 and is particularly defined in the claims.

In the preferred embodiment of our invention shown in the drawings, which illustrates our invention as applied to a switch for breaking currents of high potential, Figure 1 15 shows the switch closed, the dotted lines showing the position of the movable arm when the switch is opened. Fig. 2 shows the switch in a resetting position. Fig. 3 is a detail of the arc-displacing device, and Fig. 4 is a detail 20 of the fuse-clamp and other parts adjacent thereto.

It is very difficult to break electric currents of high potential—for instance, ten thousand volts or more—without the generation 25 of an arc between the circuit-terminals, which will destroy or seriously impair the same. By our present invention we provide a means by which currents of very high voltage may be successfully broken. We do not 30 however, limit ourselves to a device for breaking such high-potential currents, as we are aware that our invention may be used for other purposes.

In our preferred embodiment 1 is a binding-post connected with the electric circuit and is provided with spring-jaws 2. 3 is a second binding-post connected with said electric circuit and also provided with spring-jaws 4.

5 is an arm of non-conducting material pivoted at 6 to a stationary standard 7 and having a knife projection 8, adapted to enter the jaws 4, and a second knife projection 9, adapted 40 to enter the jaws 2 when the arm 5 is swung 45 into its vertical position.

10 is a lever pivoted at 11 to the arm 5 and having a lug 12 thereon, Fig. 5. The lever 10 forms one member of a catch for holding the arm 5 in its vertical position. The other

member of the catch is in this embodiment a 50 lever 13, pivoted at 14 and having one or more teeth 15 thereon to engage said lug 12.

16 is a rod of non-conducting material movable up and down inside the arm 5 and carrying a pin 17, which passes through a slot 18 55 in lever 10.

19 is one of a pair of projections extending through slots 20 on opposite sides of arm 5. When the rod 16 is pulled down—for instance, by means of an implement hooked 60 over projections 19—the lever 10 will be pulled down and disengaged from teeth 15 on lever 13, thereby releasing the arm 5, which may then drop down to the position shown in Fig. 2. 65

21 is a conductor carried in the otherwise non-conducting arm 22, which arm is pivoted at 23 to the arm 5, and the conductor 21 is electrically connected with the knife-blade 8 and the lower block, of which it forms a part, 70 by the metallic base of the non-conducting arm 22, hinged thereto.

24 is a metallic head electrically connected with conductor 21. The head 24 has attached to it a fuse 25, and these two together 75 form one terminal of the switch. The other end of the fuse passes over and is clamped between a curved metallic portion 26 on lever 10 and an abutment 27 on the metallic block 28, carried by arm 5, which form the other 80 terminal. For additional security the end of the fuse may be looped over a pin 27^a on lever 10. This terminal 26 27 is electrically connected with block 28 and binding-post 1, but insulated from the other parts, except for 85 connection through the fuse 25.

29 is a cord connected to a handle 30 at one end and at the other end to lever 14, which together form a means for releasing the fuse from between the clamps, as by pulling down 90 the cord 29 the levers 14 and 10 will be thrown into the position shown in dotted lines in Fig. 4, thus releasing the fuse. The arm 32 will by spring 31^a be thrown down to the horizontal position shown in dotted lines in Fig. 1, which 95 will pull the fuse off from pin 27^a, and arm 22 will fall onto a rest 32, yieldingly supported in a dash-pot 33. As the arm 22 is thrown

down and the end of the fuse breaks contact with the terminal on arm 5 an arc will be formed between the fuse and said terminal. We have provided a device to control the location of the arc, said device being automatically movable when the electrical connection between the terminals is broken to displace and break the arc. This device preferably includes a receptacle, in this embodiment a non-conducting tube containing a finely-divided non-conductor, preferably a non-fusible powder, such as air-slaked lime. We do not, however, limit ourselves to these details. In the embodiment shown we provide a non-conducting holder 34, in the form of a tube, for containing the powder and run the fuse through this tube and powder, as shown in Fig. 3. The tube rests against the metallic head 24 and the end 31 of the lever 10 and is connected to the upper end of the arm 5 by a cord. When the fuse and arm 22 are released, the arm falls or is drawn down and the circuit is broken and an arc forms between the fuse and jaws 26 27. As the tube 34 falls and is drawn aside by the cord, as shown, the arc is displaced both by the movement of the tube and also because the fuse being attached to head 24 is drawn through the tube 34 as the arm 22 falls away across the line of motion of the fuse. The arc is in this way displaced, and as the air-gap between the terminals is increased it is safely broken. The tube will drop down to the position shown in dotted lines in Fig. 1. The fuse will generally be partially melted by the arc. In some cases an arc may form at each end of the tube 34; but we have found that by our invention currents of very high potential—for instance, sixty thousand volts—may be safely broken without burning out any of the parts except the fuse, which may be easily replaced. On account of the great danger from such high potentials we prefer to locate the switch out of ordinary reach, preferably higher up on the wall or switchboard than can be reached by the hand. To reset the device, a hook on the end of a pole may engage pin 19 on the rod 16 and draw the same down, thus dropping the end of the lever 10 away from the teeth 15, when the arms 5 and 22 will rotate on the pivot 6 to the position shown in Fig. 2, the arm 22 being supported by the rest 35. The powder-tube 34 may then be put in the position shown in Fig. 2 and the fuse inserted. The whole device can then be swung up into the position shown in Fig. 1, thus closing the circuit.

To prevent the movement of arm 5 while the circuit is closed, we have provided an automatic lock for said arm. In the embodiment shown in the drawings this consists of a foot 36 on rod 16, which foot is engaged from below by a projection 37, carried by arm 22, thus preventing the rod 16 from being drawn down as long as arm 22 is in its raised position. When the switch is raised from the position shown in Fig. 2 to that shown in Fig. 1, the circuit is closed through said switch and the same is locked in position, as rod 16 cannot be pulled down until the circuit is broken, when the fall of arm 22 moves lug 37 from beneath foot 36, thus releasing the lock.

We are aware that very many changes may be made in the construction herein disclosed without departing from the spirit of our invention, particularly in the device for displacing the arc when the current is broken, and we therefore do not desire to limit ourselves to any of the details herein disclosed.

We claim—

1. In a circuit-breaking device, two relatively movable terminals located in a line considerably out of the vertical, a fuse connecting said terminals and holding them relatively stationary, a receptacle of non-conducting material surrounding and confining said fuse and held in position thereby, and means for releasing one end of said fuse and retracting one of said terminals thereby permitting said receptacle to fall and laterally displace any arc formed.

2. In a device for breaking an electric circuit, in combination, a circuit-terminal, a conductor connected therewith but separable therefrom, a receptacle of non-conducting material located near said terminal and surrounding said conductor, and means for moving said receptacle automatically out of alignment to displace the arc laterally when said conductor is separated from said terminal.

3. In a switch, in combination, a movable member engaging with circuit-contacts, and a second movable member for making and breaking the circuit through the terminals of said switch, and means controlled by said second movable member for releasing said first member.

Signed at Pittsfield, Massachusetts, this 20th day of July, 1900.
